mesne assignments, to Jersey Production Research
Company, Tulsa, Okla., a corporation of Delaware

Filed Apr. 9, 1959, Ser. No. 805,231
8 Claims. (Cl. 166—42)

The present invention is directed to a method for increasing the production of hydrocarbons such as oil and gas. More particularly, the invention is concerned with increasing production of oil and gas from subsurface earth formations. In its more specific aspects, the invention relates to a method for treating a well to increase the permeability to oil of a sand packed fracture or barrier such that increased production of oil is obtained from the well.

This application is a continuation-in-part of U.S. Serial No. 749,222, entitled "Increasing Production of Oil," filed July 17, 1958, for John W. Graham, Joseph S. Osoba, and Patrick H. Monaghan, now abandoned.

The present invention may be briefly described as a method for fracturing a subsurface earth formation with oil containing a sand propping agent in which the sand propping agent is lodged in the resulting fractures to maintain them open. The feature of the present invention is rendering the sand propping agent water-wet whereby the permeability of the said propping agent to oil is increased and increased production of oil is obtained.

The present invention is also directed to forming a barrier of sand or finely divided particulate material around a well casing lining the walls of a borehole or around a screen and liner arranged in an unconsolidated horizon or zone from which formation sand is produced with the hydrocarbons. The barrier may suitably be formed in the well bore around the casing or in a cavity formed by removal of sand with the produced well fluids or in a cavity produced by washing out the formation with fluids introduced into the well. The feature of the present invention is rendering the sand or finely divided particulate material water-wet prior to its being or after it has been formed into a barrier.

The sand propping agent or finely divided particulate material is rendered water-wet either prior to being lodged in the fractures or after it is lodged in the fractures.

There are various ways of practicing the present invention. In one mode of the present invention, the sand is wet with water by spraying it with water or immersing it in water such that each sand grain will have a coat of water which remains with it. The water-wet sand is then suspended in the oil which is to be used to form a barrier in the well or to fracture the subsurface earth formation and then the suspension of water-wet sand and oil is pumped into a well which penetrates subsurface earth formations and is introduced or forced into the formation under a sufficient pressure when it is desired to fracture or crack the formation. As a result, the water-wet sand particles lodge in the formation or in the resulting fractures and serve to maintain them open such that oil may be produced from the formation through the open fractures. By virtue of the sand being water-wet, its relative permeability to oil is increased, thereby resulting in increased production of oil from the formation.

Another mode of practicing the invention involves wetting the sand with an aqueous solution of an anionic surface active or wetting agent which may contain sodium chloride. The water-wet sand is then suspended in an oil carrier vehicle and thereafter the suspension is pumped into a well penetrating the subsurface earth formation which is to be fractured under a sufficient pressure to

2

lift the overburden and fracture or crack the particular subsurface earth formation which it is desired to fracture. As a result the water-wet sand lodges and packs in the fractures to maintain them open and the water-wet sand is rendered more permeable to oil, allowing subsequent increased production of oil from the fractured formation.

In a still further mode of practicing the invention, a subsurface formation may be fractured with a suspension of sand propping agent in oil to fracture the formation and to lodge the sand propping agent in the resulting fracture. Thereafter the fractures are treated with an aqueous or oily solution containing an anionic surface active or wetting agent to render the sand propping agent preferentially wettable by water. Thereafter the treated sand propping agent is contacted with water which may be formation or produced water or may be water introduced through the well bore into the formation. As a result, the sand propping agent is water-wet and its relative permeability to oil is increased, allowing subsequent increased production of oil from the fractured formation.

In another and preferred method of practicing the present invention, a solution of water, anionic surface active agent, and sodium chloride is made up by agitating water, surface active agent, and sodium chloride. Thereafter sand in an amount of at least 0.1 pound per gallon of solution is added and the mixture is agitated and then allowed to stand for a period ranging from about one to about ten hours. The excess water is then removed from the sand and the water-wet sand is then dispersed into an oil carrier vehicle such as kerosene in an amount of at least one pound of wet sand per gallon of the oil carrier vehicle. The resulting suspension is then pumped under high pressure into a well against a formation to be fractured which causes the fracturing of the formation and lodges the water-wet sand in the fractured formation. As a result, the relative permeability of the sand to oil is increased, allowing increased production of oil from the fractured formation.

As a modification of the preferred mode, a suspension of oil, sand, and anionic wetting agent may be formed and employed to fracture a selected earth formation penetrated by a well bore by pumping the suspension of oil and sand containing the anionic wetting agent into a well bore penetrating the selected formation under a pressure to cause fracturing of the formation and to cause the sand to lodge in the fractures and maintain them open. Thereafter the sand is contacted with water which may either be produced water or water introduced from the borehole to contact the sand, thereby increasing the relative permeability of the sand in the fractures to oil such that on subsequent production of oil increased amounts thereof are obtained.

As a still further modification of the present invention the finely divided particulate material or sand is pumped or otherwise introduced into a well after being wet with water as a suspension in an oily vehicle. The suspension is introduced into a zone from which hydrocarbons are producible but which also is of such nature that substantial quantities of sand are also produced with the hydrocarbons such as oil or gas. The suspension of water-wet sand may be pumped down a cased well and out through perforations therein for lodgement back of the casing to form a barrier of water-wet sand around the casing to prevent production of sand from the productive zone. Under this mode of operation, pump pressures may be controlled to avoid imposing a fracturing pressure on the formation although both fracturing and formation of a barrier to prevent sand production may be performed simultaneously. Alternatively, the water-wet sand may be flowed as a suspension down the annulus between the borehole wall and the casing for deposition of the water-wet sand in sand and hydrocarbon productive zone.

The water-wet sand may be dropped or dumped into the well for deposition into a barrier and thereafter a screen and liner may be washed down and arranged in the barrier.

The sand, when used for formation of a barrier in a well bore, may also be introduced down a tubing string or other pipe string either before or after being wet with water as described herein.

In the present invention where a barrier is deliberately formed to prevent sand being produced, it is now possible to remove the barrier without recourse to drilling operations since circulation of fluid, such as oil as a suspending medium, down the well and through the barrier may allow removal of the barrier.

This aspect of the present invention where a barrier is formed with the water-wet sand is quite important and useful in that many oil wells produce from unconsolidated or loosely consolidated sand formations or zones such that a considerable quantity of sand is produced or entrained in the well fluids such as oil and water. This entrained sand moving with the well fluids at the velocity thereof erodes pipes, connections, chokes, and pumps and deposits in tankage requiring frequent cleaning thereof with consequent removal from service.

In practicing the present invention, the sand or particulate material employed is usually round Ottawa sand having a mesh size (U.S. Sieve Series) in the range from about 10 to about 40 mesh. Equivalent sand to the round Ottawa may be used and different mesh size may be employed. For example, angular sand grains may be used and either angular or round sand having mesh sizes from about 10 to about 80 may be used. The sand may be between 20-40 mesh, 40-60 mesh, or 60-80 mesh or may be distributed over the range of mesh sizes. The 20 to 40 mesh will be preferred.

An amount of sand employed should be at least about 0.1 pound per gallon of the oil used as a suspending medium and/or as a fracturing liquid. Amounts of sand up to about 5 pounds per gallon oil may be used. For example, about 10,000 to 15,000 pounds of sand may be used for each 10,000 gallons of the fracturing oil.

The fracturing oil or the suspending vehicle for the sand may be a refined petroleum fraction such as gasoline or kerosene or may be gas oil or crude oil such as that found on the lease or a different crude oil. Under some situations, a reduced or topped crude may be used. It will be preferred, however, to use a refined oil.

The surface active or wetting agent is one of the anionic type, examples of which are the reaction product of tall oil and methyl taurine, a commercial product which is an anionic amine neutralized surfactant, alkyl aryl sulfonate such as marketed under the trade names of Tide, Chiffon detergent, and other anionic surfactants of a similar type. As examples of other anionic surfactants agents may be mentioned the salts of alkyl aryl sulfonates such as sodium xylene sulfonate, keryl benzene sulfonate, monobutyl biphenyl sulfonate, these sodium salts being commonly known as Naxonate G, Kreelon 4D, and Areskap 300, respectively. Alkyl sulfates such as Tergitol 08, which is the sodium sulfonate of 2 ethyl hexanol-1 may be used.

Other useful anionic surface active agents include the alkyl sulfonates such as Tergitol EH which is sodium sulfonates of 2 ethyl hexanol, Petrowet R and Duponol 189, both aliphatic hydrocarbon sodium sulfonates, sulfonated amides and amines as illustrated by Igepon TK-42, sodium N-methyl-N octyl taurate, Dianol N and Sulframin DHL both fatty amide sulfonates, sulfated and sulfonated esters known to the trade as Nekal NS, trihexyl sulfotriarbyllate, and Triton X-200, an alkyl aryl ester sulfonate. Where the metallic ion of the salt is not given, it is to be understood that the sodium salt is used. The amount of surface active agent employed may range from about 0.2 to about 5 percent by weight based

on the water. A preferred amount may range from about 0.5 percent to about 2 percent by weight.

Inasmuch as introduction of water into a formation may cause formation damage due to swelling of interstitial clay, it is contemplated that sodium chloride may be included in the water used to treat the sand either before or after it is lodged in place. It is contemplated, therefore, that sodium chloride in an amount in the range from about 0.05 to about 5 pounds per gallon of water may be used. A preferred amount may range from about 0.1 to about 2 pounds per gallon of water.

The invention will be further illustrated by reference to FIGURES 1 to 4, which are graphs showing the relationship between the amount of oil in the produced fluid and the relative permeability to oil for water-wet and oil-wet sand columns.

The degree to which wettability influences oil permeability is seen more clearly if the relative permeability to oil is expressed as a function of the percent of oil in the flowing stream. The following relation makes the transformation:

$$F_o = \frac{\mu K_o}{K_o + \frac{\mu_o}{\mu_w} K_w}$$

where

F_o = fraction of oil in the flowing stream

K_o = relative permeability to oil

K_w = relative permeability to water

$\frac{\mu_o}{\mu_w}$ = oil-water viscosity ratio

This was done for the two wettability conditions, water wet sand and oil-wet sand, and for viscosity ratios of 1, 10, and 60. FIGURES 1 to 4 illustrate the results.

The dependence of oil permeability upon wettability at an oil-water viscosity ratio of 1 is shown in FIG. 1. The plot illustrates that:

(1) The relative permeability to oil is greater when water is the wetting phase than when oil is the wetting phase if the oil in the produced exceeds 50 percent. For example, if water is the wetting phase and the flowing stream contains 3 percent water (97 percent oil in produced fluids) the permeability to oil is 33 percent of the single-fluid value. On the other hand, if oil is the wetting phase, the permeability to oil is only 14 percent of the single-fluid value. Thus, at 3 percent water in the produced fluid, the water-wet condition gives an oil permeability 2.4 times greater than the oil-wet condition.

(2) If the flowing stream contains less than 50 percent oil, both wettability conditions give about the same oil permeability.

FIGURES 2 and 3 show the effect of wettability on oil permeability when the oil-water viscosity ratios are 10 and 60. From these figures it can be seen that an increase in the viscosity ratio sharply increases the range of flowing stream compositions over which the water-wet condition is desirable, i.e., gives a higher oil permeability than the oil-wet condition.

In many oil fields, the oil-water viscosity ratio is close to one. However, there are other fields in which the ratio is much greater than one. For example, one field in Texas has an oil-water viscosity ratio of about 60. If the oil productive formation is fractured and contains sand which is oil wet, oil production for any stream composition and hence for the entire life of the well would be reduced.

In order to illustrate the invention further, a copper tube 153 cm. long and having a 1.11 cm. inside diameter was packed with 20 to 40 mesh round Ottawa sand. The column of sand was then saturated with distilled water and then two constant rate pumps, one delivering water and the other delivering oil were used to obtain steady state drainage and imbibition relative permeability data. After these data were obtained, they were interpreted as shown in FIGURE 4, from which may be observed that the oil

permeability is always greater when water is the wetting phase.

The invention will be further illustrated by reference to sand operations in which oil wells were hydraulically fractured employing the present invention. In these operations wells in West Texas were fractured. In the first operation, 350 gallons of fresh water, 30 pounds of Tide, and 35 pounds of sodium chloride were agitated for ten minutes to form a solution. Thereafter, 10,000 pounds of 20 to 40 mesh round Ottawa sand was added to the solution and agitated for 20 minutes, following which the mixture was allowed to stand overnight. After standing overnight, excess water was drained from the water-wet sand and then the water-wet sand was dispersed in 10,000 gallons of refined oil and employed to fracture a selected formation, following which the fractured formation was flushed with lease crude.

Another similar fracturing operation was employed with water-wet sand excepting that 15,000 pounds of 20 to 40 mesh water-wet sand were used.

Another well in West Texas was treated in accordance with present invention employing the following procedure. Ninety gallons of fresh water had eight pounds of Tide and eight pounds of sodium chloride added thereto, which were agitated for fifteen minutes to form a solution. Twenty-five hundred pounds of 20 to 40 mesh sand were added to the solution and the mixture agitated for fifteen minutes and allowed to stand overnight. The following morning excess water was drained from the water-wet sand and the water-wet sand was then dispersed in 2,000 gallons of refined oil and pumped into the well to fracture a selected formation. The water-wet sand lodged in the fractures and the fractured formation was flushed with lease crude. As a result of this treatment, increased production was obtained.

An attempt was made in a well in the Gulf Coast of Texas to fracture the well and pack it with sand simultaneously using sand which had not been wet with water. This attempt was unsuccessful since flow of sand into the well bore occurred before a screen and liner could be run and set. The present invention was then employed. A solution containing 16 pounds of sodium chloride and 10 pounds of a commercial detergent ("Tide") in 100 gallons of fresh water was employed to treat and wet with water 10,000 pounds of sand. The water-wet sand was then employed to fracture the formation and form a barrier with the screen and liner in place.

The 10,000 pounds of water-wet sand as described supra in 9,820 gallons of 30° API gravity lease crude oil were used in the operation. After running in and placing sucker rods and pump, the well produced 105 barrels per day of oil with 6% salt water over an extended period of time which indicates high productivity for this successful operation in accordance with the present invention.

As stated previously, the sand may be wetted with the water prior to dispersal in the suspending or fracturing liquid. In this manner, each sand grain is coated with a film of water that protects the sand surface from becoming oil wet. However, wet sand is difficult to disperse in oil in that the sand grains become bonded together by water. Therefore, it is desirable to add an anionic interfacial tension-reducing agent to the water used to wet the sand and to cause preferential wetting of the sand with water.

In treating fractured formations which contain oil-wet sand, the fractured formation may be subjected to a treatment as follows:

- (1) Inject water containing about 10,000 p.p.m. of sodium chloride;
- (2) Inject lease crude containing about 2 percent of anionic surface active agent; and
- (3) About thirty minutes after the treatment with the surface active agent inject water containing about 10,000 p.p.m. sodium chloride.

This method insures that water of suitably low salinity contacts the now water-wet sand.

The pressures employed to inject the water, the lease crude, and the second batch of water should be sufficiently low that new fractures are not created and existing fractures are not disturbed.

In such treatment, 1,000 gallons of water may be used followed by 2,000 gallons of the crude containing the anionic surface active agent and then followed by 2,000 gallons of the water.

As illustrations of the increased permeability of the sand to oil possible in the practice of the present invention, oil permeabilities caused by restoration of water wetness of 90 percent, 112 percent, 34 percent, and 78 percent have been obtained. In other instances, increased permeabilities of as great or greater than the values reported were also obtained.

From the foregoing description and several examples, it will be clear that the present invention is quite advantageous and useful in that by the practice of the present invention increased and maximum recoveries of hydrocarbons such as oil and gas and the like may be obtained from fractured formations by insuring that the sand propping agent in the fractures is water-wet and therefore is provided with increased permeability to oil. Also, it is clear that the present invention prevents or suppresses sand flow from an unconsolidated zone into a well.

The invention is also advantageous in that the water-wet sand is pumpable and does not form packs or bridges across the well which resist removal from the well. In short, wetting of the sand renders it fluid which may increase the ease of fracturing and particularly the spotting of a body of the sand into a selected zone where sand production is a problem. In one operation, it became necessary to stop the pumps while sand was being introduced. After about 45 minutes, it was found that the sand had not packed into an immobile mass and formed a bridge but had retained mobility, thus avoiding a sand removal job.

40 The nature and objects of the present invention having been completely described and illustrated, what we wish to claim as new and useful and secure by Letters Patent is:

1. In a method for fracturing a subsurface earth formation with oil containing a suspended sand propping agent 45 in which the sand propping agent is lodged in and maintains the resulting fracture open, the improvement which comprises wetting the sand propping agent with water whereby the permeability of the sand propping agent to oil is increased and increased production of oil is obtained.

50 2. A method in accordance with claim 1 in which the sand propping agent is wet with water prior to being lodged in the fracture.

3. A method in accordance with claim 1 in which the sand propping agent is wet with water after being lodged 55 in the fracture.

4. A method for increasing the production of oil from a subsurface earth formation which comprises wetting a sand propping agent with water, admixing the water-wet sand propping agent with an oil carrier vehicle to form a 60 suspension of water-wet sand propping agent in said vehicle, then fracturing said subsurface earth formation with said suspension to lodge said water-wet sand propping agent in the resulting fractures and maintain them open whereby the permeability of said lodged sand propping

65 agent to oil is increased, and then producing oil in increased amounts from said fractured formation.

5. A method in accordance with claim 4 in which the water contains an anionic surface active agent.

6. A method in accordance with claim 4 in which the 70 water contains an anionic surface active agent and sodium chloride.

7. A method for increasing the production of oil from a subsurface earth formation which comprises fracturing said subsurface earth formation with a suspension of oil 75 and a sand propping agent to lodge said sand propping

agent in the resulting fractures, treating the lodged sand propping agent with an anionic surface active agent to render the lodged sand propping agent preferentially wettable by water, contacting the treated sand propping agent with water whereby the permeability of said treated, water contacted sand propping agent to oil is increased, and then producing oil in increased amounts from said fractured formation.

8. A method for increasing the production of oil from a subsurface earth formation which comprises fracturing said subsurface earth formation with a suspension of oil and a sand propping agent containing an anionic surface active agent, to lodge said sand propping agent in the resulting fractures, the sand propping agent being rendered preferentially wettable by water by said anionic surface active agent, contacting the lodged sand propping agent with water whereby the permeability of said water contacted sand propping agent to oil is increased, and then producing oil in increased amounts from said fractured formation.
